UNITED STATES PATENT OFFICE.

HENRY L. COAKLEY, OF NEW YORK, N. Y.

AEROPLANE.

1,288,384.

Specification of Letters Patent. Patented Dec. 17, 1918.

Application filed September 4, 1917. Serial No. 189,697.

To all whom it may concern:

Be it known that I, HENRY L. COAKLEY, a citizen of the United States, and a resident of the city of New York, borough of Manhattan, in the county and State of New York, have invented a new and Improved Aeroplane, of which the following is a specification.

This invention relates to airplanes, and my improvements are directed more particularly to means for obtaining longitudinal, lateral and directional stability in true aeronautical combination for all natural conditions of flight in which an airplane needs to be balanced.

It is only by the intimate association of interconnected elements in the three different directions of an airplane that the factors which make for stability in any one direction will also at the same time make for stability in each of the other two directions of the airplane, whereby true inherent stability can be created in an airplane.

Inherent stability, as comprehended by me, consists in so devising the wings or sustentation surfaces of the airplane, in fixed relation, that the airplane will thereby be enabled to maintain its flight attitude, whether that be horizontal, or inclined as for banking, climbing or descending.

To this end I provide pairs of wings which are swept either forwardly or backwardly throughout their whole extent, so that sustentation is accorded by said wings as well directionally as longitudinally and laterally with respect to the center of gravity of the airplane. Also said wings are angled vertically, with their inner sections of greater span, forming a dihedral angle, and their outer sections, of less span, forming each, with a central section, a reverse dihedral angle.

But the leading and rear edges of the wings, at each side of the airplane, are in parallel planes, which are equally inclined to the longitudinal axis of the airplane, with the leading edges of the wings throughout one side of the airplane in the same plane. Thus my improved aerofoils or supporting surfaces may be said to comprise wings which extend out laterally in opposite directions, in symmetrical, angled relation, both in plan and in elevation, the angles including a central dihedral section and outward sections of reverse dihedral.

The proportional spans of the central sec-

tions and outward sections afford pressure areas of different extents, the central sections having greater area than the outer sections, to thus exercise substantially equal leverage about the longitudinal axis of the airplane. Therefore the pressure against a central section at one side of the airplane is equaled by the concurrent pressure against an outer section at the opposite side, whereby said sections tend to form a balancing couple to maintain equilibrium in any attitude of the airplane.

Movable aerofoils are provided for longitudinal, lateral and directional control of the airplane.

Other features and advantages of my said invention will hereinafter appear.

In the drawings:

Figure 1 is a plan view of an airplane embodying that form of my invention wherein swept forward wings are employed.

Fig. 2 is a front elevation thereof, and Fig. 3 is a side elevation.

Fig. 4 is a plan view of that embodiment of my invention having swept back wings, of arrow type.

Fig. 5 is a front elevation thereof, and Fig. 6 is a side elevation.

Fig. 7 is a plan view of a modification, in the form of a multiplane.

Fig. 8 is a front elevation thereof, and Fig. 9 is a side elevation.—Fig. 10 is a front elevation of another modification in the form of a multiplane.

First describing the form of my invention which appears in Figs. 1 to 3, I have there depicted a biplane whose aerofoils are swept forward, and are angled to form the central, dihedral sections 1, 2, and the outward sections 3, 4; the latter, respectively, with sections 1, 2, forming reverse dihedral angles.

The dihedral and reverse dihedral angles provided are equal in degree, and the sections constituting those angles are of like chord, but the central sections 1, 2, which are of equal span, each exceed by a like extent the span of their respectively adjacent sections 3, 4. Hence the areas of the central sections exceed the areas of the outer sections, and the proportional relation between these areas must depend upon the extent of span of the entire aerofoil supporting surface, and on the vertical location of the center of gravity.

Essentially, the balancing couples provided in horizontally swept or raked wings,

which are angled as described, require that the angles of attack of all the sections comprising the wings be equal in degree, as measured longitudinally, throughout the 5 span of the wings. Hence, in front aspect, it will be apparent that air pressures met squarely by all sections of the aerofoil will give equal support over the entire span of said aerofoil; while all deviations in pressure 10 direction will be met by righting couples composed of a positive section at each side of the longitudinal axis of the airplane; the other sections offering the less resistance as a balancing couple meets pressures exerted other than longitudinally. Thus a stable condition is established in the 15 airplane, whether its attitude be horizontal in normal flight, or inclined as in banking for making turns, or inclined for climbing 20 or descent. The longitudinal angling or rake of the wings is desirable, as thereby the center of gravity of the airplane may be located longitudinally between vertical transverse planes bounding the chord extremities 25 of the aerofoil.

Movable ailerons, as 7, 8, are respectively mounted along the rear edges of the sections 3, 4, and are intended merely for the purpose of correcting variations in normal balance 30 or load in the airplane. The airplane body or fuselage 9, which may be of usual character, is shown as carrying the horizontal rudders 5, 5, and vertical rudder 6, for adjusting the airplane vertically and directionally. 35

The aerofoil of the arrow type airplane shown in Figs. 4, 5 and 6, is composed of the central sections 1^a, 2^a, and outer sections 3^a, 4^a, these sections arranged in vertical angularity like the sections 1, 2, 3, 4, but horizontally arranged to give a swept back character to the wings. In their vertically angled arrangement these wings correspond with the swept forward wings previously described. 45

The rear edges of the sections 3^a, 4^a, which are arranged in a plane inclined to the longitudinal axis of the airplane, are provided with movable ailerons, which may be rectangular, of sufficient surface area to enable them to function as control means for adjusting the airplane vertically, laterally and directionally; whereby the use of tail wings and vertical rudder may be dispensed with. 50

In carrying out the principle of angled wings, established by my invention, in the form of a multiplane machine such as indicated in the example of Figs. 7, 8 and 9, and also in Fig. 10, the vertically angled arrangement of the wings is retained as in the previously described examples, but the particular superposed relation of said wings equally embodies the same principle of balance for an airplane. 55

In the examples of my invention illus-

trated in the drawings I have shown its application to biplanes and multiplanes, but obviously the principle involved in the production of my improved aerofoil surfaces is also applicable to monoplanes. 70

Variations may be resorted to within the spirit and scope of my said invention and parts thereof used without others.

I claim:—

1. In an airplane, a supporting aerofoil 75 comprising fixed opposite wings having central sections in dihedral relation, and outer sections in equal reverse dihedral relation with connecting central sections, whereby all the sections present the same angle of incidence in the line of flight, to provide balancing couples, the leading edges of said wings throughout each side of the airplane occupying respective planes which are inclined equally to the longitudinal axis of 80 the airplane.

2. In an airplane, a supporting aerofoil comprising fixed opposite wings having central sections in dihedral relation, and outer sections in equal reverse dihedral relation 90 with connecting central sections, whereby all the sections present the same angle of incidence in the line of flight, to provide balancing couples, the leading edges of said wings throughout each side of the airplane occupying respective planes which are inclined equally to the longitudinal axis of the airplane 95 and movable members for controlling the longitudinal, lateral and directional movements of the airplane. 100

3. In an airplane, a plurality of supporting aerofoils, each comprising opposite wings having connected sections in dihedral relation, and outer sections in equal reverse dihedral relation with connecting central sections, whereby all the sections present the same angle of incidence in the line of flight, 105 to provide balancing couples, the leading edges of said wings throughout each side of the airplane, occupying respective planes which are inclined equally to the longitudinal axis of the airplane. 110

4. In an airplane, a plurality of supporting aerofoils, each comprising opposite wings having connected sections in dihedral relation, and outer sections in equal reverse dihedral relation with connecting central sections, whereby all the sections present the same angle of incidence in the line of flight, 115 to provide balancing couples, the leading edges of said wings throughout each side of the airplane, occupying respective planes which are inclined equally to the longitudinal axis of the airplane, and movable members for controlling the longitudinal, lateral and directional movements of the airplane. 120

5. In an airplane, a supporting aerofoil comprising opposite wings having connected central sections in dihedral relation, and outer sections, in equal reverse dihedral re- 130

- lation with connecting central sections, whereby all the sections present the same angle of incidence in the line of flight, to provide balancing couples, the leading and rear edges of said wings throughout each side of the airplane occupying respective parallel planes, which are inclined equally to the longitudinal axis of the airplane.
- 5 6. In an airplane, a supporting aerofoil comprising opposite wings having connected central sections in dihedral relation, and outer sections, in equal reverse dihedral relation with connecting central sections, whereby all the sections present the same angle of incidence in the line of flight, to provide balancing couples, the leading and rear edges of said wings throughout each side of the airplane occupying respective parallel planes, which are inclined equally to the longitudinal axis of the airplane, and movable members for controlling the longitudinal, lateral and directional movements of the airplane.
- 10 7. In an airplane, a plurality of supporting aerofoils, each comprising opposite wings having connected sections in dihedral relation, and outer sections in equal reverse dihedral relation with connecting central sections, whereby all the sections present the same angle of incidence in the line of flight, to provide balancing couples, the leading and rear edges of said wings throughout each side of the airplane occupying respective parallel planes, which are inclined equally to the longitudinal axis of the airplane, and movable members for controlling the longitudinal, lateral and directional movements of the airplane.
- 15 8. In an airplane, a plurality of supporting aerofoils, each comprising opposite wings having connected sections in dihedral relation, and outer sections in equal reverse dihedral relation with connecting central sections, whereby all the sections present the same angle of incidence in the line of flight, to provide balancing couples, the leading and rear edges of said wings throughout each side of the airplane occupying respective parallel planes, which are inclined equally to the longitudinal axis of the airplane, and movable members for controlling the longitudinal, lateral and directional movements of the airplane.
- 20 9. An airplane having a supporting aerofoil whose span comprises a central dihedral portion with opposite side portions in equal, reverse dihedral relation therewith, to provide balancing couples, the leading edge of said aerofoil extending out in opposite directions from its center in respective angles which each occupy a plane that is inclined to the longitudinal axis of the airplane.
- 25 30 In testimony whereof, I have signed my name.

HENRY L. COAKLEY.
